LABELING MACHINE

Charles H. Oslund, Worcester, Mass.

Application February 3, 1936, Serial No. 62,114

15 Claims. (CL 216—54)

This invention relates to labeling machines, and more particularly to machines of the type having pickers which transfer the labels from a label magazine to the articles to be labeled.

In labeling machines of this type it is customary to apply adhesive to the pickers by means of a suitable roll, this roll being passed over the surface of the pickers before they engage the labels. Unless the roll contacts with the pickers evenly and uniformly, it is impossible to provide the desired smooth coating of adhesive. In actual practice it is very difficult to obtain exact alignment between the pickers and the roll, and it often happens that wear on the various bearings and guides will accentuate the difficulty.

It is accordingly one object of the invention to provide a labeling machine which will apply a smooth and even coating of adhesive to the labels in spite of misalignment between the pickers and the roll.

In one form of labeling machine which is often used for labeling glass bottles, the bottle is placed upon a stationary support where it remains during the labeling operation. After the label has been transferred to the bottle, the label is wiped firmly against the bottle by means of suitable wiper blades which are controlled by cam devices. With bottles of different shapes and sizes it is necessary to impart different movements to the wiper blades. In prior machines of this type such changes in movement require extensive and inconvenient alterations and adjustments in the various parts.

It is accordingly a further object of the invention to provide a labeling machine which can be easily and conveniently adapted to articles of various shapes and sizes.

The ordinary picker mechanism applies adhesive to the end portions only of the labels, and this is usually sufficient with bottles of circular cross-section. With flat bottles however it is desirable to apply adhesive to the central portions of the labels also. While various mechanisms have been proposed for this purpose, they have in general proven to be complicated, expensive, and subject to many difficulties in operation.

It is accordingly a further object of the invention to provide a simple, inexpensive and reliable mechanism for applying adhesive to the central portions of the labels.

With these and other objects in view, as will be apparent to those skilled in the art, the invention resides in the combination of parts set

forth in the specification and covered by the claims appended hereto.

Referring to the drawings illustrating one embodiment of the invention and in which like reference numerals indicate like parts,

Fig. 1 is an elevation of a labeling machine, viewed from the right hand side;

Fig. 2 is a front elevation of the machine with certain parts removed;

Fig. 3 is a section on the line 3—3 of Fig. 1;

Fig. 4 is a fragmentary front elevation showing the wiping mechanism in a different part of its cycle;

Fig. 5 is a section on the line 5—5 of Fig. 1;

Fig. 6 is a section on the line 6—6 of Fig. 1;

Fig. 7 is a section on the line 7—7 of Fig. 1;

Fig. 8 is a section on the line 8—8 of Fig. 1;

Fig. 9 is an elevation of the machine, viewed from the left hand side, certain parts omitted for clearness of illustration;

Fig. 10 is a fragmentary front elevation with certain parts omitted to show the center-gumming mechanism;

Fig. 11 is a detail showing the center-gumming operation;

Fig. 12 is a detail showing the path of movement of the center-gummer;

Fig. 13 is an elevation of certain of the operating levers and their cams viewed from the right hand side;

Fig. 14 is an enlarged front view showing the operation of the gum roll;

Fig. 15 is a detail showing the automatic correction of misalignment between the gum roll and pickers; and

Fig. 16 is a fragmentary front view showing a modified wiping operation for use with flat bottles.

In the drawings I have shown a machine suitable for labeling glass bottles, the bottles being placed in the machine and removed therefrom by hand. The embodiment illustrated comprises a base 20 on the front portion of which there is mounted a frame or bracket 21. This bracket carries at its upper end a V-shaped bottle rest 22 in which the bottle 23 may be supported in a substantially horizontal position during the labeling operation. It will be noted that the neck of the bottle is pointed toward the front where it can be easily grasped by the operator.

On the rear portion of the base 20 there is mounted a vertical column 25 which carries at its upper end a horizontal platform 26. A suitable label magazine 27 is mounted on this platform, the magazine serving to support a stack

20

25

30

35

40

45

55

of labels 28 above and spaced from the bottle 23. Labels are transferred from the magazine to the bottles by means of a pair of spaced horizontal picker blades 30 which are reciprocated vertically. The magazine 27 is preferably provided with the usual toggle links 31 and operating handle 32 whereby the magazine may be raised slightly when it is desired to prevent contact of the pickers with the labels.

10 The picker blades 30 are fastened at their rear ends to a slide 33 which is slidably supported by means of spaced vertical guides 35. These guides are supported at their lower ends by the base 20, and their upper ends are secured to a bracket 36 which projects forwardly from the column 25. The slide 33 is reciprocated vertically by a suitable cam mechanism. In the preferred construction illustrated, a double-forked arm 37 is pivoted at its rear end to the column 25, the front portion of the arm being connected to the slide 33 by means of a pair of links 38, as shown particularly in Figs. 1 and 5. A vertical guide 40 extends between the bracket 36 and a lower bracket 41 carried by the base 20, and this guide 40 supports a vertically reciprocable slide 42 which is connected to the arm 37 by means of a link 43. The slide 42 is provided with a cam roller 45 which engages the periphery of a cam 46. A tension spring 47 (Figs. 1 and 13) connects the arm 37 with the column 25 and holds the roller 45 in contact with the cam 46. This cam is mounted on a longitudinal shaft 48 which is rotatably supported by the bracket 41 and by a bracket 50 mounted on the base 20 in front of the cam.

35 The shaft 48 is rotated by any suitable means, and for this purpose there is provided a transverse shaft 51 which is connected to the shaft 48 by a pair of miter gears 52. The transverse shaft is rotatably supported in bearings 53 carried by 40 the base 20, and on one end of the shaft there is mounted a large pulley 55. An electric motor 56 is mounted on the upper platform 26, and this motor drives a small pulley 57 through suitable speed-reducing gears 58. The pulley 57 is connected to the pulley 55 by means of a belt 59.

50 In order to hold the label on the bottle while the pickers 30 are being withdrawn upwardly there is provided a label gripper 61 having a facing 62 of sponge rubber or other suitable material. The label gripper is pivoted at its rear end to the front portion of the bracket 36 by means of a transverse pin 63, and means is provided to oscillate the label gripper about its pivot in synchronism with the movements of the pickers.

55 For this purpose the label gripper is formed with a rearwardly projecting arm 64 which is connected by means of a link 65 with the front end of an arm 66. The rear end of this arm 66 is pivotally secured to the column 25, and a cam roller 67 is mounted on the arm and engages the periphery of a cam 68 on the transverse shaft 51. A tension spring 70 maintains the necessary contact between the roller and the cam. The link 65 is preferably made telescopic, and is urged to its extended position by a surrounding coiled compression spring 71. With this construction the label gripper will apply a yielding pressure to the label and the bottle.

70 Means is provided to apply adhesive to the upper surfaces of the pickers 30 before they engage each label. For this purpose the usual gum box 72 is mounted on a platform 13 above the bracket 36. This gum box is provided with the usual cylinder 75 which is partially immersed in the adhesive and constantly rotated by means of gears

16 and a sprocket wheel 77, the latter being connected by a chain 78 to a sprocket wheel 79 on the shaft 51, as shown particularly in Fig. 9. Adhesive is transferred from the cylinder 75 to the pickers by means of a gum roll 81 which is supported by a carrier having a pair of spaced arms 82. These arms are connected at their lower ends by a transverse shaft 83 which is rotatably supported in the bracket 50, and one of the arms is provided with a rearwardly extending arm 84 which is connected by a link 85 to the front end of a lever 87, the rear end of this lever being pivotally supported on the column 25. The lever 87 is provided intermediate its length with a cam roller 88 which engages the periphery of a cam 89 mounted on the transverse shaft 51. A tension spring 90 is connected to the arm 87 to hold the roller in contact with the cam, as best shown in Fig. 13. A gear 92 is mounted on the gum roll 81 and when the gum roll is in contact with the cylinder 75 this gear meshes with a gear 93 on the cylinder. This causes the gum roll to rotate and thus become coated with adhesive from the cylinder.

25 The gum roll is held in contact with the pickers and the cylinder with a yielding pressure, and the parts are preferably so constructed and arranged that either end of the gum roll can yield independently of the other to compensate for inaccuracies in alignment. For this purpose, a finger 95 is pivotally attached to the upper end of each arm 82 and projects forwardly therefrom. Each finger is provided with a laterally projecting lug 96 which supports an adjustable screw 97. A coiled tension spring 98 connects each finger with the corresponding arm, movement of the finger under the influence of the spring being limited by the screw 97. As shown particularly in Fig. 14, the shaft 99 of the gum roll 81 fits loosely in holes 100 formed in the fingers 95. With this 40 construction, the shaft can move angularly with respect to the fingers, and each finger can pivot independently on its respective arm. Consequently the gum roll will contact firmly with the pickers 30, as shown in Fig. 15, despite slight 45 misalignment.

50 After the label has been applied to the bottle by the pickers, the ends of the label have to be wiped or pressed against the bottle. For this purpose there is provided a crosshead 102 which is slidably supported for vertical reciprocation in suitable spaced guides 103 on the frame 21. In order to drive this crosshead, a crank 104 is mounted on the front end of the longitudinal shaft 48, and this crank is joined to the crosshead by an upwardly extending connecting rod 105. At the top of the crosshead and on opposite sides of the bottle rest 22 there are mounted two wiper arms 107, each arm having a wiper blade 108 of rubber or other suitable material on 60 its upper end.

65 In the operation of the wiping mechanism, the wiper blades are given a lateral motion in addition to their vertical motion. Furthermore, it is necessary to vary the lateral motion for different sizes and shapes of bottles. In the embodiment illustrated, the lower end of each wiper arm 107 is secured to the rear end of a pin 109 which is rotatably supported in the crosshead 102. To the front end of each pin there is secured a laterally extending arm 110. The arms 110 are connected by means of links 112 to the ends of a transverse bar 113 mounted on the upper end of a vertical slide 114. This slide 114 is arranged for vertical reciprocation in the 75

crosshead 102. In order to control the movements of the slide 114, a suitable cam mechanism is provided. In the preferred construction illustrated, a longitudinal shaft 115 is rotatably supported in the frame 21 at a lower elevation than the shaft 48 so as to avoid interference with the crank 104. A gear 116 is mounted on the shaft 48 directly in the rear of the crank 104, and this gear meshes with a gear 117 on the rear end of the shaft 115. These gears preferably have a one-to-one speed ratio. On the front end of the shaft 115 there is mounted a cam 118 which engages a cam roller 119 on the lower end of the slide 114. A spring 120 maintains the proper contact between the roller and the cam. The crank 104 imparts a vertical reciprocation to the crosshead 102, and the cam 118 imparts a vertical reciprocation to the slide 114, but there is a slight difference between these two movements. Consequently the slide has a slight reciprocation relative to the crosshead, and as a result of this relative motion, the links 112 serve to oscillate the arms 110 and 107. This oscillation in combination with the vertical movement causes the wiper blades 108 to be drawn outwardly and downwardly over the end portions of the label, as indicated particularly in Fig. 4, thus pressing the label firmly against the bottle. In order to allow a slight yielding of the wiper arms 107 they are preferably made in articulated form and normally held rigid by a tension spring 120. The cam mechanism at the front of the machine is preferably enclosed by a removable vertical plate 122 (Fig. 1).

If the size or shape of the bottle is changed, it will usually be necessary to alter the motion of the slide 114 and occasionally the shape of the wiper arms 107. The slide motion can easily be changed by replacing the cam 118 with a slightly different cam. This is a very simple matter, since the parts are readily accessible at the front of the machine after the plate 122 is removed. In Fig. 16 there is shown the movement of the wiper blades in applying a label to a flat bottle, the various parts being identified by the reference numerals previously used, with the addition of the suffix "a".

The picker blades 30 apply adhesive only to the end portions of each label, but in some cases it is desirable to apply adhesive also to the central portion of the label. This may be accomplished by the mechanism illustrated in Figs. 9 to 12 inclusive. In this mechanism there is shown a center-gummer in the form of a flat blade 124 which is coated with adhesive and pressed against the lower label in the magazine 27 at substantially the same time as the picker blades 30. The center-gummer is then moved downwardly ahead of the pickers and laterally to allow the pickers to descend without interference. For this purpose the blade 124 is mounted on the upper end of a substantially vertical arm 125 which is pivotally connected at its lower end to a bracket 126 mounted on a vertical bar 127. This bar is slidably supported for vertical reciprocation at one side of the bottle rest in upper and lower guides 128 and 129 mounted respectively on the bracket 36 and the frame 21. In order to reciprocate the bar there is provided an arm 131 which is pivotally supported at its rear end by the column 25, the front end of this arm being connected to the lower end of the bar 127 by means of a link 132. A cam roller 133 is mounted on the arm 131 to engage the periphery of a cam 134 secured to the transverse shaft 51. A tension spring 135

maintains the roller in proper contact with its cam.

In addition to the vertical movement imparted to the blade 124 by the bar 127, this blade is given a lateral movement also. For this purpose a cam roller 137 is mounted on the arm 125, and this roller is arranged to engage a stationary cam 138 supported by the upper guide 128. A tension spring 139 holds the roller against the cam. These parts are so arranged that as the bar 127 is moved upwardly, the cam 138 will swing the arm 125 to the right in Fig. 10 and bring the blade to a position directly over the bottle and between the pickers 30.

The operation of the invention will now be apparent from the above disclosure. As soon as the label has been wiped against the bottle by the wiper blades 108, the label gripper 61 will swing upwardly, releasing the bottle. The operator will thereupon remove the labeled bottle and immediately place an unlabeled bottle in the rest 22. While the wiping action is taking place, the picker blades 30 are moving upwardly. The center-gummer 124 is moved upwardly by the action of the cam 134 and laterally by the action 25 of the cam 138, passing beneath the adjacent picker blade and into the space between the picker blades, its upward velocity being momentarily higher than that of the picker blades until it reaches the same elevation. During the 30 continued upward motion of these parts, the gum roll 81 passes rearwardly over their upper surfaces and coats them with adhesive, the springs 98 yielding independently to ensure a firm and accurate contact. The gum roll continues its rearward movement until it engages the rotating cylinder 75 and receives a new coating of adhesive, the roll being rotated by the action of the gears 92 and 93. The continued 35 upward movement of the pickers and the center-gummer brings these parts into contact with the bottom label 28. The center-gummer starts to move downwardly slightly ahead of the pickers, having left a coating of adhesive on the central 40 portion of the label. As the pickers descend, the lower label adheres to their upper surfaces, and the center-gummer swings to the left and out of the path of the pickers. As the pickers and the label approach the bottle, the label gripper 61 will swing downwardly and forwardly, clamping the central portion of the label firmly against the bottle. The pickers will then move upwardly, leaving the label, and the wiper blades 108 will swing inwardly and downwardly, wiping the ends 45 of the label against the bottle. Near the bottom of their movement the wiper blades swing outwardly, and they remain in this outward position while they are traveling upward again. This lateral movement of the wiper blades can be controlled as desired by varying the shape of the cam 119. Upon completion of the wiping action, the label gripper will swing upwardly, the operator will remove the labeled bottle, and the 50 cycle will be repeated.

It will be noted that the independently yieldable springs 98 will maintain a firm and accurate contact of the gum roll with the pickers irrespective of slight misalignment. The cam 118 can be easily and conveniently replaced by a different 55 cam to adapt the machine to bottles of various shapes and sizes. The center-gumming mechanism is simple and inexpensive to manufacture, and thoroughly reliable in operation.

Having thus described my invention, what I 75

claim as new and desire to secure by Letters Patent is:

5. A labeling machine comprising a label magazine, pickers to receive labels from the magazine, a roll to apply adhesive to the pickers, and independently yieldable supports for the opposite ends of the roll to ensure proper alignment of the roll with the pickers.
10. A labeling machine comprising a stationary label magazine, movable pickers to transfer labels from the magazine to the articles to be labeled, a roll movable over the pickers to apply adhesive thereto, and independently yieldable supports for the opposite ends of the roll to ensure proper alignment of the roll with the pickers.
15. A labeling machine comprising a stationary label magazine, movable pickers to transfer labels from the magazine to the articles to be labeled, a gum box, a cylinder rotatable in the gum box, a roll to transfer adhesive from the cylinder to the pickers, and independently yieldable supports for the opposite ends of the roll to ensure proper alignment of the roll with the pickers.
20. A labeling machine comprising a label magazine, pickers to receive labels from the magazine, a carrier, a pair of spaced fingers independently pivoted to the carrier, springs yieldably holding the fingers in predetermined positions with respect to the carrier, and a roll loosely supported at its ends in the fingers and arranged to apply adhesive to the pickers, the springs yielding independently to ensure proper alignment of the roll with the pickers.
25. A labeling machine comprising a rest for the articles to be labeled, two vertically reciprocable members located beneath the rest, a pair of label-wiping devices mounted on one of said members and located at opposite sides of said rest, connections between the other of said members and the devices arranged to move the devices laterally, a longitudinal rotatable shaft beneath the members, a cam removably mounted on the front end of the shaft and arranged to reciprocate one of the members, and means to reciprocate the other of said members.
30. A labeling machine comprising a rest for the articles to be labeled, two vertically reciprocable members located beneath the rest, a pair of label-wiping devices mounted on one of said members and located at opposite sides of said rest, a longitudinal rotatable shaft beneath the members, a cam removably mounted on the front end of the shaft and arranged to reciprocate one of the members, and means to reciprocate the other of said members.
35. A labeling machine comprising a rest for the articles to be labeled, two vertically reciprocable members located beneath the rest, a pair of label-wiping devices mounted on one of said members and located at opposite sides of said rest, a longitudinal rotatable shaft beneath the members, a cam removably mounted on the front end of the shaft and arranged to reciprocate one of the members, and means to reciprocate the other of said members.
40. A labeling machine comprising a rest for the articles to be labeled, two vertically reciprocable members located beneath the rest, a longitudinal rotatable shaft beneath the members, a cam removably mounted on the front end of the shaft and arranged to reciprocate one of the members, and means to reciprocate the other of said members.
45. A labeling machine comprising a rest for the articles to be labeled, two vertically reciprocable members located beneath the rest, a longitudinal rotatable shaft beneath the members, a cam removably mounted on the front end of the shaft and arranged to reciprocate one of the members, and means to reciprocate the other of said members.
50. A labeling machine comprising a rest for the articles to be labeled, two vertically reciprocable members located beneath the rest, a longitudinal rotatable shaft beneath the members, a cam removably mounted on the front end of the shaft and arranged to reciprocate one of the members, a gear on the shaft and located at opposite sides of said rest, and connections between the cam-actuated member and the devices arranged to move the devices laterally.
55. A labeling machine comprising a rest for the articles to be labeled, two vertically reciprocable members located beneath the rest, a longitudinal rotatable shaft, a crank on the shaft, a connecting rod extending upwardly from the crank to one of the members to reciprocate the same, a gear on the shaft, a second longitudinal rotatable shaft at a lower elevation than the first shaft, a gear on the second shaft in mesh with the first gear, a cam on the front end of the second shaft and arranged to reciprocate the other member relative to the crank-actuated member, a pair of label-wiping devices pivotally supported by the crank-actuated member and located at opposite sides of said rest, and connections between the cam-actuated member and the devices arranged to oscillate the devices laterally about their pivots.
60. A labeling machine comprising a rest for the articles to be labeled, a crosshead located beneath the rest, a longitudinal rotatable shaft, a crank on the front end of the shaft, a connecting rod extending upwardly from the crank to the crosshead to reciprocate the crosshead vertically, a gear on the shaft in the rear of the crank, a second longitudinal rotatable shaft at a lower elevation than the first shaft, a gear on the second shaft in mesh with the first gear, a slide supported for vertical reciprocation in the crosshead, a cam on the front end of the second shaft and arranged to reciprocate the slide relative to the crosshead, a pair of label-wiping devices pivotally supported by the crosshead and located at opposite sides of said rest, and connections between the slide and the devices arranged to oscillate the devices laterally about their pivots.
65. A labeling machine comprising a rest for the articles to be labeled, a label magazine above and spaced from the rest, a pair of spaced pickers located above the rest and below the magazine, means to move the pickers up and down between the rest and the magazine, a center gummer, means to move the gummer into the space between the pickers as they move upwardly, means to apply adhesive to the pickers and the gummer, means to move the gummer upwardly with the pickers to contact with a label in the magazine, and means to move the gummer downwardly and then laterally to one side of the pickers so that the pickers may move downwardly without interference into a position close to an article on the rest.
70. A labeling machine comprising a rest for the articles to be labeled, a label magazine above and spaced from the rest, a pair of spaced pickers located above the rest and below the magazine, means to move the pickers up and down between the rest and the magazine, a center gummer, means to move the gummer into the space between the pickers as they move upwardly, means to apply adhesive to the pickers and the gummer, means to move the gummer upwardly with the pickers to contact with a label in the magazine, means to move the gummer downwardly, the gummer starting to move downwardly slightly in advance of the pickers, and means to move the gummer laterally as it moves downwardly.
75. A labeling machine comprising a rest for the articles to be labeled, a label magazine above and spaced from the rest, a pair of spaced substantially horizontal pickers located above the rest and below the magazine, means to reciprocate the pickers vertically, a member located at

one side of the rest, means to reciprocate the member vertically, a center-gummer supported by the member, a stationary cam arranged to move the gummer laterally as it is moved vertically, the parts being so constructed and arranged that the gummer will enter the space between the pickers from beneath the pickers, and means to apply adhesive to the pickers and gummer.

13. A labeling machine comprising a rest for the articles to be labeled, a label magazine above and spaced from the rest, a pair of spaced substantially horizontal pickers located above the rest and below the magazine, means to reciprocate the pickers vertically, a member located at one side of the rest, means to reciprocate the member vertically, a center-gummer supported by the member, a stationary cam arranged to move the gummer inwardly above the rest as it moves upwardly, the parts being so constructed and arranged that the gummer will enter the space between the pickers from beneath the pickers, and means to apply adhesive to the pickers and gummer.

14. A labeling machine comprising a rest for the articles to be labeled, a label magazine above and spaced from the rest, a pair of spaced substantially horizontal pickers located above the

rest and below the magazine, means to reciprocate the pickers vertically, a member located at one side of the rest, means to reciprocate the member vertically, a center-gummer pivotally supported by the member, a stationary cam arranged to swing the gummer inwardly about its pivot and above the rest as it moves upwardly and thus into the space between the pickers from beneath the pickers, and means to apply adhesive to the pickers and gummer.

15. A labeling machine comprising a rest for the articles to be labeled, a label magazine above and spaced from the rest, a pair of spaced substantially horizontal pickers located above the rest and below the magazine, means to reciprocate the pickers vertically, a member located at one side of the rest, means to reciprocate the member vertically, a substantially vertical bar pivotally supported at its lower end on the member, a center-gummer mounted on the upper end of the bar, a stationary cam arranged to swing the bar inwardly about its pivot as the member moves upwardly and thus bring the gummer above the rest and into the space between the pickers from beneath the pickers, and means to apply adhesive to the pickers and gummer.

CHARLES H. OSLUND
